UNITED STATES PATENT OFFICE.

LEOPOLD KASSANDER, OF NEW YORK, N. Y., ASSIGNOR TO NATHAN MANUFACTURING COMPANY, OF NEW YORK, N. Y.

OIL CUP.

Application filed November 11, 1922. Serial No. 600,197.

To all whom it may concern:

Be it known that I, LEOPOLD KASSANDER, a citizen of the United States, residing in the borough of Manhattan, city, county, and 5 State of New York, have invented certain new and useful Improvements in Oil Cups, of which the following is a description.

The invention herein described and claimed relates particularly to oil cups, such as oil 10 cups employed in oiling the guides of locomotive engines, although also adapted for use in connection with other receptacles.

Oil cups embodying my invention are 15 greatly superior to other types of oil cups with respect to stronger and better construction, economy of manufacture and greater efficiency. The covers of the oil cups now in use on locomotive engines tend to jar loose because of the great engine 20 vibration, thus exposing their interiors to dust, cinders and other undesirable substances, which pass with the oil to the bearings and cause them serious injury. In addition to the increased cost of maintenance 25 of engines, caused by this imperfect oiling, there are also the expense and trouble of frequently furnishing oil cup covers to replace those that are lost. Further, it is very 30 desirable that oil cups should be so constructed as to be not only strong, durable and efficient, but also to be readily and quickly filled with oil.

It is the object of this invention to satisfy 35 the foregoing requirements and its characteristic advantages will appear from the drawings and the following description.

Fig. 1 is a side elevation in section and 40 Figs. 2, 3 and 4 are top plan views of an oil cup embodying the invention, the plan views showing the cover and cap in different positions.

The body 1 of the oil cup is preferably 45 of cylindrical form and contains the central hub 2 which is connected to the body 1 by the ribs 3, 4. Preferably the body, hub and ribs are integral, as by a single casting. Shank 5 is suitably connected to the lower part of the body 1 and contains 50 outlet passage 6 for the oil, the shank being preferably exteriorly threaded for tight connection with the bearing or other part to be oiled, not shown. Screw spindle 7 is concentric to the body 1 and moves within hub 2, spindle and hub being appropriately 55 threaded. Upon the spindle and secured to

it as by pin 8 is the handle 9 of inverted cup form, having ears 10, 10. The spindle contains slot 11 to cause closer fit with the hub. Lower part 12 of spindle 7 is conical to slidably fit in conical or tapered seat 60 13 of outlet passage 6.

Cover 14 with thumb lug 15 rests on and covers top of oil cup body 1. Into opening 16 in cover fits lower annular ring 17 of cap 18, which cap also has upper annular 65 extension 19, adapted to contain lower part of spring 20, the upper part being held by the inverted cup-shaped handle 9. The spring thus presses downward the cap upon the cover 14 and also tends to hold the 70 spindle in position.

Opening 16, cover 14 and cap 18 are eccentrically mounted with respect to the body 1 of the oil cup, spindle 7 being in the center of the body and passing through opening 75 16 and annular extension 19 of cap 18, said extension being mounted concentrically with the spindle. Opening 16 is adapted to swing on annular ring 17 of cap 18 as a pivot and cover 14 will then swing eccentrically 80 to the spindle. The cover and cap are removably connected together by pin 21 in annular ring 17 engaging shallow groove 22 in the cover. Pin 23 on rib 3 is adapted to engage slot 24 in annular ring 17 so as 85 to hold the annular ring and cap 18 fixed with respect to body 1.

When the oil cup is closed, as shown in Figs. 1 and 2, cover 14 rests upon the top of body 1 and cap 18 covers opening 16, pins 21 and 23 engaging respectively slot 24 and 90 groove 22. Turning the thumb lug 15 of the cover in either direction will cause pin 21 to slip out of shallow groove 22 and as cover 14 swings around on annular ring 17, said 95 ring and cap 18 being fixed with respect to body 1 because of pin 23 being in slot 24, there appears a crescent shaped aperture 100 in the top of body 1, Fig. 3, into which oil may be poured for filling purposes. While pin 21 engages groove 22, the cover and cap may be raised against the pressure of spring 20, so that pin 23 is disengaged 105 from slot 24 and the cover and cap may then be rotated about the spindle, the annular extension 19 and the cover swinging concentrically and the cap eccentrically with respect to the spindle.

Among other advantages of the construction is the ease with which the cover may 110

be displaced for the purpose of filling with oil. A slight pressure upon the thumb lug will disengage the cover from the cap and will permit the cover to swing about the 5 annular extension of the cap as a pivot, thus creating a crescent shaped opening into which the oil can be poured. Further, there is a tight fitting and positive closure of the oil cup, by reason of the pressure 10 of the spring upon the cap, which in turn holds the cover securely upon the body. All danger of losing or misplacing the cover or other parts is eliminated while the oil cup can be readily taken apart by unscrewing the spindle from the hub. When 15 it is desired to permit oil to flow through the outlet passage 6 and into the bearing to be lubricated, the handle 9 is turned to cause the spindle and its conical lower part 20 12 to move upward and away from the seat 13. The outlet passage is closed by turning the handle in the opposite direction.

The invention is adapted for use with 25 lubricating matter other than oil and the embodiment herein described is merely illustrative, various modifications and changes being possible without departing from the substance of the invention herein 30 described and claimed.

I claim:

1. A receptacle having a cover with opening therein, a central spindle in the receptacle, said spindle passing through the opening and being eccentric thereto, and means 35 for closing said opening.

2. A receptacle having a cover with open-

ing therein and a hub, a cap, and a central spindle in the receptacle, said spindle passing through the opening and the hub and being concentric with the hub but eccentric to the opening and the cap.

3. An oil cup having a cover with opening therein and a hub, a cap, a central spindle in the receptacle, said spindle passing through the opening and the hub and being concentric with the hub but eccentric to the opening and cap, an annular ring on said cap fitting within said opening and adapted to serve as a pivot for the cover and an annular extension on said cap co-operating with a spring and the spindle to cause pressure against the cap.

4. A receptacle with a cover adapted to swing eccentrically to a central spindle in said receptacle and means cooperating with said cover to keep closed said receptacle.

5. A receptacle with a central spindle adapted to regulate the flow of contents therefrom, and a cap mounted on said spindle and having an annular ring, and a cover adapted to rotate around said ring.

6. A receptacle with central hub and outlet passage, a spindle movable within the hub and adapted to close the passage, a cover mounted eccentrically to the spindle, a cap mounted eccentrically to the spindle and with annular ring adapted to fit in opening in the cover, a cup-shaped handle on the spindle, a compression spring between the handle and the cap, means for securing cap on cover and means for securing cover on receptacle.

LEOPOLD KASSANDER.
